UNITED STATES PATENT OFFICE.

FRANK L. GORMLEY, OF BOSTON, AND BERNICE B. TERRILL, OF WINTHROP, MASSACHUSETTS.

LIFTING-JACK.

No. 921,234.

Specification of Letters Patent.

Patented May 11, 1909.

Application filed November 14, 1908. Serial No. 462,713.

To all whom it may concern:

Be it known that we, FRANK L. GORMLEY and BERNICE B. TERRILL, citizens of the United States of America, and residents of 5 respectively, Boston and Winthrop, both in the county of Suffolk and State of Massachusetts, have invented certain new and useful Improvements in Lifting-Jacks, of which the following is a specification.

10 This invention relates to lifting jacks and particularly to that class of joints known as ratchet screw jacks and it has for its object the provision of a locking mechanism which is adapted to effectually retain the jack in 15 raised position under a load, this locking mechanism being so constructed as to be temporarily released to effect a lowering of the jack when the operating lever is manipulated under certain conditions.

20 The invention consists in certain novel features of construction and arrangement of parts which will be readily understood by reference to the description of the drawings and to the claims hereinafter given.

25 Of the drawings: Figure 1 represents a horizontal section of a jack embodying the features of this invention, the cutting plane being on line 1—1 on Fig. 2 looking in the direction of the arrow. Fig. 2 represents a 30 vertical section of the same, the cutting plane being on line 2—2 on Fig. 1 looking in the direction of the arrow. Fig. 3 represents a vertical section through the operating lever and ratchet mechanism, the cutting plane being on line 3—3 on Fig. 1 looking in the direction of the arrow. Fig. 4 represents a horizontal section on line 4—4 on 35 Fig. 2 looking in the direction of the arrow. Fig. 5 represents an enlarged vertical section, the cutting plane being on line 5—5 on Fig. 1, looking in the direction of the arrow. Fig. 40 Fig. 6 represents an enlarged vertical section, the cutting plane being on line 6—6 on Fig. 1 looking in the direction of the arrow. Fig. 45 Fig. 7 represents a partial longitudinal section, the cutting plane being on line 7—7 on Fig. 5, looking in the direction of the arrow, and Fig. 8 represents a longitudinal section, the cutting plane being on line 8—8 on Fig. 6 50 looking in the direction of the arrow.

Similar characters designate like parts throughout the several figures of the drawings.

In the drawings, 10 represents a hollow 55 standard provided with an enlarged base portion 11. To the exterior periphery of

the standard 10 is fitted a sleeve 12 capable of being vertically moved on said standard 10, the shoulder 13 of the base 11 of the standard 10 limiting the movement of said 60 sleeve in one direction while a stop latch 14 pivotally mounted upon said sleeve 13 with one end extending through a slot therein and adapted to engage an annular stop groove 15 cut into the periphery of the 65 standard 10 limits the movement of the sleeve 12 in the opposite direction.

The upper end of the standard 10 is provided with a nut 16 to which is threaded the screw 17 to the upper end of which is keyed 70 a bevel gear 19 meshing with another bevel gear 20 formed on or secured to a lateral shaft 21 extending through a bearing 22 formed upon a removable plate 23 secured to the head 24 screwed or otherwise fastened 75 upon the upper end of the sleeve 12.

It is obvious that by the rotation of the shaft 21, the screw 17, through the medium of the gears 19 and 20, will be moved about its axis in the nut 16 causing the head 24 with 80 its sleeve 12 to be raised and lowered relative to the standard 10. The lifting jack set forth in the foregoing description is of common construction, the present invention being limited to the method of operating the 85 revolvable shaft 21 and locking it to prevent accidental movement when the jack is supporting a load.

In order to provide a suitable locking device for the shaft 21 the periphery of the 90 bearing 22 in which said shaft 21 is mounted is eccentric to the axis of said shaft as clearly indicated in Fig. 5. This bearing 22 is provided near its inner end with a slot 25 extending from its bore to its periphery, one 95 end of said slot, as, for instance, the upper end, being of slightly greater width than the other or lower end. An annular ring 26 is fitted to the periphery of the bearing 22 and is adapted to cover the slot 25 and revolve 100 about the periphery of said bearing. This annular ring is provided with a series of gear teeth 27 which mesh with an intermediate gear 28 revolvable about a stud 29 screwed into the bearing 22. Upon the 105 shaft 21 beyond the outer end of the bearing 22 is revolvably mounted a gear ring 30, the teeth 31 of which mesh with the teeth of the intermediate gear 28. This annular ring 30 is also provided with a series of peripheral 110 ratchet teeth 32, one face of each of which is cut away, as shown in the drawings.

On the reduced ends of the shaft 21 is mounted a forked lever 33, said lever being freely movable about the axis of said shaft. Between the arms of the bifurcated ends of 5 the lever 33 is a ratchet member 34 keyed or otherwise secured to the shaft 21. The forked lever or member 33 is provided with a pair of radial ears 35 in which is mounted a pin 36 supporting a reversible pawl member 10 37. This member 37 is normally in the position shown in Fig. 3 and is retained in this position by means of the bolt 38 mounted in a socket 39 in the member 33, said bolt being pressed outwardly by means of a spring 40 15 so that the V-shaped end of the bolt engages with one of the inclined faces on the end of the pawl 37.

The bolt or locking member 38 is prevented from turning in its socket by means 20 of the screw 41 extending into a groove extending longitudinally of said bolt.

In the position shown in Fig. 3, the forked member 33 is provided with a suitable socket in which is mounted the operating handle 42. 25 When the various parts are in the position indicated in Fig. 3, an up-and-down or pump-handle motion imparted to the operating lever 33—42 will effect the raising of the head 24 relative to the standard 10 on which the 30 sleeve 12 rides during the lifting movement. During this movement the shaft 21 rotates in the direction of the arrow indicated on the section of said shaft in Fig. 5 of the drawings. It is obvious that in the movement of the 35 shaft in the direction thus indicated by the arrow the ball 43 will be raised into the wider part of the slot 25 into the position shown in dotted lines in said Fig. 5, thus permitting a free movement of said shaft 21.

40 The side walls of the slot 25 are inclined toward each other as they approach the shaft 21, as indicated clearly in Fig. 7, so that when the shaft is removed from its bearing 22 the ball 43 will not become displaced. As soon as the rotation of the shaft 45 21 (in the direction of the arrow on Fig. 5 of the drawings) ceases the ball 43 will drop into a narrower part of the slot 25 and become firmly impinged upon the periphery of 50 the shaft 21 and the inner wall of the annular ring 26, thereby locking the two members 21—26 together so that the shaft cannot be moved in a direction opposite to that indicated by the arrow on Fig. 5. It is obvious 55 therefore that should there be any tendency, owing to the excessive weight upon the jack, for the shaft 21 to move in the opposite direction, it will impinge upon the ball 43 so effectually as to prevent movement in that 60 direction. This provides an effectual locking device which prevents the jack from accidentally lowering when supporting an excessive weight. In order, however, to secure a lowering of the jack when desired, 65 the pawl 37 is provided with a lateral tooth

44 which may be made to engage with the peripheral teeth 32 of the ring 30 when the pawl 37 has been moved about its pivot 36 until the V-shaped end of the bolt 38 engages the inclined face 45 of said pawl. It is 70 obvious that under such conditions when an up-and-down or pump-handle motion is given to the operating lever 42 the ring 30 will be moved about the axis of the shaft 21 in a direction opposite to that indicated by 75 the arrows on Fig. 5 of the drawings. This movement of the ring 30 by means of the intermediate gear 28 will cause the ring 26 to be moved in the direction indicated by the arrow on Fig. 5 of the drawings and when 80 the ring 26 is thus moved the ball 43 will be lifted in the wider part of the slot 25, that is into the position indicated in dotted lines in Fig. 5, thus releasing its impinging action upon the shaft 21 and permitting the end 46 85 of the pawl to act on the ratchet wheel 34 to move the shaft 21 in a direction opposite to that indicated by the arrow on Fig. 5 and cause such a rotation of the screw 17 in the nut 16 which will lower the head 24 relative 90 to the standard 10.

By constructing lifting jacks of this class in the manner described, the accidental lowering of the head 24 on the standard 10 by an excessive load placed thereon is wholly 95 obviated while at the same time the load may be lowered at the will of the operator without difficulty.

It is believed that from the foregoing the operation and many advantages of the invention will be fully understood without further description.

Having thus described our invention, we claim:

1. In a lifting jack, the combination of a 105 stationary member; a movable member thereon; means for operating said movable member including a lateral shaft; a ring freely revoluble about said shaft and operable with said operating means when lowering said movable member; and a member interposed between said ring and shaft adapted to grip the latter under abnormal conditions to prevent the rotation of said shaft. 110

2. In a lifting jack, the combination of a 115 stationary member; a movable member thereon; means for operating said movable member including a lateral shaft; a bearing for said shaft provided with a pocket deeper 120 at one end than the other; a ring freely revoluble about said bearing and operated by the lowering movement of said operating means; and a member in said pocket interposed between said ring and shaft adapted 125 to grip the latter under abnormal conditions to prevent the rotation of said shaft.

3. In a lifting jack, the combination of a 130 stationary member; a movable member thereon; means for operating said movable

member including a lateral shaft; a clutch member engaging said shaft adapted to prevent the accidental lowering of said movable member; an annular ring revoluble about an axis eccentric to the axis of said shaft; a rotatable member interposed between said ring and shaft and normally adapted to impinge upon said shaft; and means controlled by the lowering of said operating means for 10 moving said ring to release the impinging of said rotatable member on said shaft.

4. In a lifting jack, the combination of a stationary member; a movable member thereon; means for operating said movable member including a lateral shaft; a ratchet secured to said shaft; an oscillating member on said shaft; a pawl on said member for operating said ratchet; a bearing for said shaft provided with a slot extending from its 20 periphery to its bore, said slot being deeper at one end than the other; a ring surrounding said bearing and covering said slot; a rotatable member within said slot and normally engaging said ring and shaft; and 25 means carried by said pawl for moving said ring about said bearing when desired.

5. In a lifting jack, the combination of a stationary member; a movable member thereon; means for operating said movable member including a lateral shaft; a ratchet secured to said shaft; an oscillating member on said shaft; a pawl on said member for operating said ratchet; a bearing for said shaft provided with a slot extending from its 30 periphery to its bore, said slot being deeper at one end than the other; an annular gear ring surrounding said bearing and covering said slot; a rotatable member within said slot and normally engaging said ring and shaft; a second annular gear revoluble on said shaft and provided with peripheral teeth; a gear interposed between said annular gears and meshing with both; and means carried 35 by said pawl for engaging said peripheral teeth.

6. In a lifting jack, the combination of a stationary member; a movable member thereon; means for operating said movable member including a lateral shaft; a ratchet secured to said shaft; an oscillating member on said shaft; a pawl on said member for operating said ratchet; a bearing for said shaft provided with a slot extending from its 40 periphery to its bore, said slot being deeper at one end than the other; an annular gear ring surrounding said bearing and covering said slot; a rotatable member within said slot and normally engaging said ring and shaft; a second annular gear revoluble on 45 said shaft and provided with peripheral teeth; a gear interposed between said annular gears and meshing with both; and means carried by said pawl for engaging said peripheral teeth during the lowering of the movable

7. In a lifting jack, the combination of a stationary member; a movable member thereon; means for operating said movable member including a lateral shaft; a ratchet secured to said shaft; an oscillating member 70 on said shaft; a double-ended pawl on said member for operating said ratchet; a bearing for said shaft provided with a slot extending from its periphery to its bore, said slot being deeper at one end than the other; a ring surrounding said bearing and covering said slot 75 provided with an annular gear; a rotatable member within said slot and normally engaging said ring and shaft; a second annular gear revoluble on said shaft and provided 80 with peripheral teeth; a gear interposed between said annular gears and meshing with both; means carried by said pawl for engaging said peripheral teeth; and a device adapted to normally retain said teeth-engaging device 85 out of engagement therewith.

8. In a lifting jack, the combination of a stationary member; a movable member thereon; means for operating said movable member including a lateral shaft; a ratchet 90 secured to said shaft; an oscillating member on said shaft; a double-ended pawl on said member for operating said ratchet; a bearing for said shaft provided with a slot extending from its periphery to its bore, said slot being 95 deeper at one end than the other; a ring surrounding said bearing and covering said slot provided with an annular gear; a rotatable member within said slot and normally engaging said ring and shaft; a second annular 100 gear revoluble on said shaft and provided with peripheral teeth; a gear interposed between said annular gears and meshing with both; means carried by said pawl for engaging said peripheral teeth; and a spring actuated member adapted to normally retain 105 said teeth-engaging device out of engagement therewith.

9. In a lifting jack, the combination of a stationary member; a movable member 110 thereon; means for operating said movable member including a lateral shaft; a ratchet secured to said shaft; an oscillating member on said shaft; a pawl on said member for operating said ratchet; a bearing for said shaft 115 provided with a slot extending from its periphery to its bore, said periphery being eccentric to the axis of said shaft and said slot being deeper at one end than the other; a ring revolvably mounted upon said bearing periphery; a toothed ring on said shaft; means carried by said pawl for moving said toothed ring about said shaft when desired; and means interposed between said rings to cause motion to be imparted from one to the other. 120

10. In a lifting jack, the combination of a stationary member; a movable member thereon; means for operating said movable member including a lateral shaft; a ratchet secured to said shaft; an oscillating member 130

on said shaft; a pawl on said member for operating said ratchet; a bearing for said shaft provided with a slot extending from its periphery to its bore, said periphery being eccentric to the axis of said shaft and said slot being deeper at one end than the other; a ring revolvably mounted upon said bearing periphery; a toothed ring on said shaft; means carried by said pawl for moving said 10 toothed ring about said shaft when desired; and means interposed between said rings to

cause one of them to be moved in one direction by the movement of the other in the opposite direction.
